UNITED STATES PATENT OFFICE.

ALBERT BLAUVELT, OF CHICAGO, ILLINOIS.

ALARM APPARATUS FOR AUTOMATIC SPRINKLER SYSTEMS.

1,184,714.

Specification of Letters Patent.

Patented May 30, 1916.

Application filed November 9, 1907. Serial No. 401,468.

To all whom it may concern:

Be it known that I, ALBERT BLAUVELT, a citizen of the United States, residing at Chicago, Cook county, Illinois, have invented 5 certain new and useful Improvements in Alarm Apparatus for Automatic Sprinkler Systems, of which the following is a specification.

My invention relates to apparatus through 10 which a continued reduction of pressure in the supply pipe of a wet pipe sprinkler system, and consequent flow of water through the automatic valve thereof to such apparatus for a certain length of time, will operate an alarm.

The object of my invention is to provide 15 an apparatus or attachment of this character which is capable of overcoming many of the difficulties experienced in actual practice and caused by dirt or sediment in the 20 sprinkler supply water which causes leakage and injury at the valve seats, also water hammer and fire pressure, which according to present practice, frequently send in false 25 alarms. Moreover, my attachment is so constructed that it is absolutely self-draining, so that it will drain itself promptly after 30 each operation and will not thereby be liable to freeze even although located in an exposed or cold location. Furthermore, by the 35 use of my invention I am enabled to dispense with electric batteries as now commonly used and to employ magneto electric current, which is more reliable than the battery current.

Other features of advantage and utility will be apparent from the description hereinafter given.

In the drawing Figure 1 is a sectional elevation of a portion of my attachment with other parts thereof shown with broken-away portions, to expose the mechanism therein; and Fig. 2 a fragmental horizontal view, partly in section, taken on a plan immediately above the hinge E, the supplementary check valve F being removed.

Referring to the present embodiment of my invention, it will be understood that my 40 automatic valve and the alarm attachment are connected with the usual riser or main vertical supply pipe supplying the automatic sprinklers, the lower portion A thereof supplying the water to the automatic valve C and the upper portion B leading 45 from such automatic valve to the distribut-

ing pipes which, it will be understood, are provided with automatic sprinklers of any usual type. Within the casing of the automatic valve is a vertical lift swing check valve formed in two parts, of which the lower part D is hinged at E, while the other part F is connected therewith by means of the bolt d, but capable of an independent movement with respect to the portion D. Both of these parts of the check valve are 55 separate valves, the portion F being arranged to seat upon an annular seat on the check valve D, the same being preferably such as indicated at G. This valve F, which may be termed a supplementary check valve, 60 is free to move up and down within the other valve, which may be termed the main check valve and the degree of lift is regulated in suitable manner, as by means of the lugs H H, as shown in the drawings. The main 65 check valve is provided on its under surface with an annular groove I located immediately over water passageways J J formed in the bushing K, whose upper end forms a valve seat for the main check valve. These 70 passageways J communicate at their lower ends with an annular groove L which in turn communicates with the connecting pipe M. It will be understood that this connecting pipe may be short, as shown in the drawing, or may be extended to any definite distance from the riser and automatic valve at which it may be desired to locate the alarm attachment proper now to be described.

The connecting or supply pipe M is adapted 75 to communicate with the alarm attachment N and as shown in Fig. 1, such supply pipe enters a chamber O formed below the casing of the attachment, which chamber is preferably provided with a strainer such as the 80 bushing P having the series of saw slits 85 acting as strainers. The bottom of the chamber O is provided with a relief opening communicating with a chamber Q and governed by a relief valve Q, such relief 90 valve being held to its seat with a predetermined pressure by means of a spring q. The chamber O has a constant restricted communication with the chamber or reservoir R of the attachment N and also a variable restricted communication. To this end, these chambers are separated by means of a diaphragm S having a constantly open but restricted passage s forming a drain passage 95 as hereinafter made apparent, and also with 100

105

110

a passage s^1 , which is governed by means of a movable plug or stem T. This latter passage and the stem are of such relative diameters that when the stem is positioned 5 in the opening, as shown in Fig. 1, there is a restricted annular passage around the stem. When, however, such stem is raised to the dotted line position in the manner hereinafter described, the opening s^1 is no longer restricted thereby, but is opened to its full capacity. The upper end of this stem is guided in a bracket t in the chamber R and the stem is controlled in position by means of the float V, which is connected to 15 a cam W. This cam is pivoted upon said bracket t and normally bears against the upper end of the stem T. The arrangement is such that when water enters and rises in the chamber or reservoir R to an extent sufficient to raise the float V as shown in the dotted lines in Fig. 1, the cam W will be partly rotated to be free of the stem, so that the stem will rise to its elevated position seen in dotted lines, caused by the upward movement of the water entering the chamber R from the chamber O under pressure.

Referring to the operation of my apparatus and assuming that the water from the 30 riser contains floating particles or dirt and also, as is usual, fluctuates somewhat in its pressure, the main check valve, according to my invention, will not be disturbed at all by any such fluctuations, but on the contrary the same will merely cause the supplementary check valve to rise and fall in response to the fluctuations. The supplementary check valve will, to a certain extent, embed foreign matter in the soft seat 35 t, which will take care of dirt or floating particles in the water and as a matter of fact it would not be a serious objection if the supplementary check valve should leak at its seat. Thus, inasmuch as the main 40 check valve D is not lifted for each and every fluctuation of pressure, it is less likely for foreign matter to get under the seat thereof and to thus bring about a continual leakage and loss of water supply by way 45 of the passages J, L and M. This matter is of importance especially where pressure tanks are employed in fire protection practice, for it is here particularly important to avoid, as much as possible such leakage 50 and loss of water supply.

My apparatus not only takes care of the minor or normal fluctuations of water, but also to severe water hammer or any strong rise of pressure, as for example the pumping up of fire pressure, as is customary in towns having water works furnishing extra pressure at times of fire. In the event of such strong rise of pressure, it is possible that the relief afforded by the supplementary check valve F will not be sufficient and

that the main check valve D will be elevated temporarily from its seat, whereupon the water will flow through the passageways J, L and M and pass into the chamber O. For example, it will be assumed that 50 the fire pressure or water hammer pressure is in the neighborhood of one hundred pounds to the square inch, and also that the relief valve Q is set to relieve at, say, one-fourth of that pressure, thereby preventing 55 any great rise of the pressure within said chamber O. Water from this latter chamber, under reduced or controlled pressure as stated, will pass through the annular passage s^1 around the plug stem T and into 60 the chamber R. Thus flow through this annular passage is so restricted by the stem that it will not fill the chamber or reservoir R in less than, say, one-half a minute or a minute, which length of time is ordinarily 65 greater than the duration of the water hammer or period consumed in raising the fire pressure which has been referred to.

Assuming that, as is usual, a water hammer or a period consumed in raising fire pressure has not lasted more than half a minute or so, it follows that because the impulse in pipe A then ceases, the main check valve becomes free to re-seat, thus shutting off the flow of water through the passageways J, L and M, whereupon the water in the chamber R will drain off at suitably proportioned drain holes s hereinbefore referred to and through the small hole g^1 in the relief valve Q, the water eventually 95 escaping through the open drain U, thus avoiding any danger from freezing and also restoring the chamber R to a proper condition to receive a fresh partial charge of 100 water to accommodate any succeeding 105 water hammer or other temporary rise of pressure, for which it is not desired to send in an alarm.

It will be understood that it is desired to send in an alarm only in the event of continuous flow of water through the sprinkler riser, as by the opening of automatic sprinklers, whereupon the relief afforded by the supplementary check valve F will then be insufficient and the main check 110 valve D will leave its seat, permitting water to flow continuously through passageways J, L and M, through chamber O and annular opening s^1 and also through the restricted opening s into the chamber R. Of course, there will be some waste of water through the drain hole g^1 , but the same is negligible in this operation of the apparatus, for it does not affect the operation thereof. Inasmuch as the main check valve 115 D is kept continuously off its seat by the continuous flow of water through an open 120 sprinkler or sprinklers, the water in chamber or reservoir R continues to accumulate 125 until half a minute or possibly a minute has 130

elapsed, according to the predetermined plan, whereupon the water will buoy up the float V, which, when it rises into the dotted position shown, moves away the cam or detent W from the upper end of the stem T. As a result, the water flowing upwardly from the chamber O forces the stem to its dotted position, thereby opening the passage at this point to its full capacity and permitting a proportionately great increase of flow of water into the chamber R. The object of the increase of flow is to furnish motor power and it continues to rise and eventually flows through the pipe X leading from the top thereof to any suitable form of hydraulic motor, such as shown at Y, for the purpose of operating the alarm. This alarm operation may be accomplished either by causing the water motor to act directly upon an alarm bell mechanism, or mechanical signals or by connecting such water motor with any suitable magneto, such as shown at Z in the present instance. The current from the magneto may be employed to actuate alarm bells, annunciators or any other alarms or signals suitable for operation by electric current. It is thus evident that so long as there is continuous flow of water through the automatic valve, the operation of the alarm (subsequent to the delay of approximately half a minute or so, as explained) will be continuous and that, when the flow of water ceases, as by shutting off the sprinkler system subsequent to a fire, the main valve D re-seats by gravity, shutting off the flow of water by passageways J L and M, and the water in chamber R drains off through the holes s and q¹. Also the stem T falls by gravity immediately upon the cessation of the flow of water upwardly from the chamber O and the float V returns to its normal position shown as the water drains away subsequent to the gravity fall of the stem T. Thus, the chambers R and O are drained and all of the parts of the apparatus are re-set in readiness for further service.

It will be understood that the automatic valve controls the forcible motor current to what may be termed the time-delay device comprising the casing N and its associated parts, which is so constructed and arranged as to take care of ordinary conditions without sending in a false alarm and to provide for a full flow of the water to the motor, which takes place only when the automatic valve has been fully operated as in case of fire. As hereinbefore stated any suitable alarm or signaling device may be employed such as for instance, as shown in the drawings, an electric bell z¹ or an annunciator drop z².

I claim:

1. An alarm device for automatic sprinkler systems which have an automatic valve

mechanism, said device comprising a fluid pressure actuated mechanism for operating an alarm, a chamber or reservoir communicating by one opening with such fluid pressure mechanism and by another opening with said automatic valve mechanism, said chamber being also provided with a restricted leak port and otherwise closed, means for positively restricting the flow of water into said chamber during a predetermined period of time and for then removing said restriction and permitting the flow of a larger volume of water to operate the fluid pressure mechanism.

2. An alarm device for automatic sprinkler systems which have an automatic valve mechanism, said device comprising a fluid pressure actuated mechanism for operating an alarm, a chamber or reservoir communicating by one opening with such fluid pressure mechanism and by another opening with said automatic valve mechanism, said chamber being also provided with a restricted leak port and otherwise closed, means governed by the level of the water in said chamber for first positively restricting the flow thereinto, and for afterward removing said restriction and permitting the flow of a larger volume of water to operate the fluid pressure mechanism.

3. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, means for restricting the flow of water into said chamber during a predetermined period of time and then for permitting a free flow when the time of flow exceeds such period and to thereby operate the fluid pressure mechanism, said means comprising a movable stem working in the passage or inlet to said chamber and normally restricting the same, and a float co-operating with such stem to permit of the removal from such inlet and to thereby permit free passage of the water.

4. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, means for restricting the flow of water into said chamber during a predetermined period of time and then for permitting a free flow when the time of flow exceeds such period and to thereby operate the fluid pressure mechanism, said means comprising a movable stem working in the passage or inlet to said chamber and normally restricting the same, a movable de-

tent for normally holding the stem to its restricting position, and a float connected with such detent for swinging the same free of the stem to permit of its removal from such inlet to thereby permit free passage of the water.

5. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, means for restricting the flow of water into said chamber during a predetermined period of time and then for permitting a free flow when the time of flow exceeds such period and to thereby operate the fluid pressure mechanism, said means comprising a diaphragm interposed in the passage to the reservoir and having an inlet thereto, a movable stem working in said inlet and normally restricting the same to an annular passage, and a float in said chamber controlling the movement of said stem from the inlet to permit of the free passage of the water.

6. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, means for restricting the flow of water into said chamber during a predetermined period of time and then for permitting a free flow when the time of flow exceeds such period and to thereby operate the fluid pressure mechanism, said means comprising a vertically movable stem working in said inlet to the chamber and normally restricting the same, means for limiting the downward movement of the stem, a detent normally limiting the upward movement thereof and means under the control of the level of water in the reservoir for controlling said detent.

7. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, means for restricting the flow of water into said chamber during a predetermined period of time and then for permitting a free flow when the time of flow exceeds such period and to thereby operate the fluid pressure mechanism, said means comprising a vertically movable stem working in said inlet to the chamber and normally restricting the same, a guide in said reservoir for the stem which is provided

with a stop adapted to limit the downward movement of the stem, a detent normally limiting the upward movement thereof, and a float for controlling the detent.

8. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, float-operated means for permitting the flow of a small volume of water into said chamber during a predetermined period of time and for then permitting the flow of an increased volume of such water from the same source when the time of flow exceeds such period to thereby operate the fluid pressure mechanism, and means for automatically draining the reservoir.

9. An alarm device for automatic sprinkler systems which have an automatic valve mechanism, said device comprising a fluid pressure actuated mechanism for operating an alarm, a chamber or reservoir communicating respectively with such fluid pressure mechanism and said automatic valve mechanism, means for restricting the flow of water into said chamber during a predetermined period of time and then for permitting a free flow when the time of flow exceeds such period and to thereby operate the fluid pressure mechanism, said means comprising a diaphragm interposed in the passage to the reservoir and having an inlet thereto, a movable stem working in said inlet and normally restricting the same to an annular passage, said diaphragm having a restricted passage independent of said inlet, and a float in said chamber controlling the movement of said stem from the inlet to permit of the free passage of the water.

10. An alarm device for automatic sprinkler systems which have an automatic valve mechanism, said device comprising fluid pressure actuated mechanism adapted to operate an alarm, a water passage between said mechanism and the automatic valve and controlled by the latter, a reservoir interposed in said passage, a relief valve communicating with such passage to relieve pressure in excess of a predetermined degree, and a float controlled stem working in the communication with said reservoir for normally restricting the flow of water through an inlet into the reservoir but arranged to fully open the same when the water in the reservoir reaches a predetermined level and raises the float.

11. An alarm device for automatic sprinkler systems which have an automatic valve mechanism, said device comprising fluid pressure actuated mechanism adapted to operate an alarm, a water passage between said mechanism and the automatic valve

and controlled by the latter, a reservoir interposed in said passage, a relief valve communicating with such passage intermediate said automatic valve and said reservoir to relieve pressure in excess of a predetermined degree, said relief valve having a restricted drain passage, and means for

restricting the flow of water into the reservoir until the water rises to a certain level and then removing said restriction.

ALBERT BLAUVELT.
